UNITED STATES PATENT OFFICE.

JOSEPH D. FLAIG, OF BROOKLYN, IOWA.

TIE.

1,011,335.

Specification of Letters Patent. Patented Dec. 12, 1911.

Application filed April 17, 1911. Serial No. 621,608.

To all whom it may concern:

Be it known that I, JOSEPH D. FLAIG, a citizen of the United States, residing at Brooklyn, in the county of Poweshiek, State 5 of Iowa, have invented certain new and useful Improvements in Ties; and I do hereby declare the following to be a full, clear, and exact description of the invention, such as will enable others skilled in the art to which 10 it appertains to make and use the same.

This invention relates to new and useful improvements in railway ties and more especially to those constructed of cement or concrete.

15 The principal object is to provide a concrete tie having a novel reinforcing construction which is adapted to hold rail supporting plates in position, thus serving the double function of a reinforcing element and 20 a rail securing means.

Another object of the invention is to provide a reinforced concrete tie having rail supporting plates of novel construction for securing the rails in position, said tie being 25 simple in construction, economical to manufacture and durable in use.

The invention consists of certain other combinations and arrangements of parts, as will be hereinafter more fully described and 30 clearly specified in the appended claim.

In the drawings:—Figure 1 is a top plan view of my improved tie. Fig. 2 is a side elevation thereof. Fig. 3 is a detailed perspective view of one end of the tie, with the 35 reinforcing elements projecting therefrom, to more clearly illustrate the same. Fig. 4 is a sectional view on the line 4—4 of Fig. 1. Fig. 5 is a vertical sectional view of one end portion of the tie, taken on the line 5—5 40 of Fig. 2. Fig. 6 is a detailed perspective view of one of the supporting plates for the rails. Fig. 7 is a similar view of a modified form of plate.

Referring to the drawings in detail, there 45 is shown a tie 10 which is constructed of cement or concrete and which is provided with a flat upper surface 11 having a rounded lower surface and sides 12 as is more particularly shown in Fig. 3 of the drawings.

50 The object of the rounded lower surface is to insure that the tie will at all times properly seat itself when secured within the ground and adjust itself to the lay of the rails.

55 In order to secure the rails 13 to the tie, the upper surface 11 adjacent each end is

provided with inclined and raised projections 14 which are spaced apart to form transverse recesses 15 for receiving the supporting plates 16. As is more particularly 60 shown in Figs. 5 and 6 of the drawings, these plates are provided with rail receiving recesses 17 and depending sides 18 which are embedded in the longitudinal sides of the tie when molded, said depending portions being 65 provided with longitudinal openings 19 for securing the same to the reinforcing elements which retain the plates in position. These reinforcing elements comprise three longitudinal bars 20, 21 and 22 the latter of 70 which is disposed centrally of the length of the tie adjacent its lower surface and the former of which are spaced apart equi-distantly from the upper surface of the tie and disposed through the openings 19 to anchor 75 the plates 16. To hold the longitudinal bars 20, 21 and 22 in proper relation and to further reinforce the tie, a single strand of wire 23 is secured to one end of the bar 21 and is extended at right angles thereto as shown 80 at 24 and looped around the bar 20 as shown at 25, from which point is directed at an angle toward the opposite end of the tie as shown at 26 and looped around the bar 22 in a similar manner as shown at 25 and then 85 extended upwardly in a similar direction and looped around the bar 21. This is continued throughout the length of the bars and tie and the wire is of such thickness and rigidity to hold the bars in proper spaced 90 relation when the concrete is molded there-around.

In the fastening means employed for the rails 13, it will be seen that the depending portions 18 prevent movement of the securing plates 16 transversely of the tie and if desired bolts 27 may also be threaded into the plates 16 and tie for securing the rails more positively in position, through the medium of their head portions.

100 In the modification of the rail securing plates shown in Fig. 7 of the drawings, the recesses 17 for the rails and the securing bolts 27 may be provided in a similar manner but the depending portions 28 have their lower 105 ends bent or turned upwardly as shown at 29 to form hooks or apertures for receiving the longitudinal bars 20 and 21, said members being similarly embedded in the concrete and being retained upon the tie and 110 within the recess 15 by said reinforcing elements in this manner.

From the foregoing description it will be readily apparent by providing rail securing plates which are retained in position by the reinforcing means or elements such reinforcing elements serve the double function. The use of a single strand of wire for holding the longitudinal bars in proper spaced relation, also avoids the necessity of providing any special form of machinery for making the usual shear members employed in reinforcing construction and by reason of attaching the rail supporting plates to the uppermost bars by means of their depending portions, a tie is provided which may be very easily manufactured and which will be durable in use.

I claim:

A railway tie constructed of molded mate-

rial, a plurality of reinforcing bars extending longitudinally and embedded in such material, a single wire strand secured at its ends to certain of the bars and looped around the other of said wires to hold the same in proper spaced relation and rail supporting plates seated in the upper surface of the tie, said plates having depending portions embedded in the longitudinal sides of the tie and having openings through which the uppermost bars are secured.

In testimony whereof, I affix my signature, in presence of two witnesses.

JOSEPH D. FLAIG.
